UNITED STATES PATENT OFFICE.

GILBERT B. SNOW, OF ELGIN, ILLINOIS, ASSIGNOR TO THE ELGIN WIND POWER AND PUMP COMPANY, OF SAME PLACE.

WINDMILL.

SPECIFICATION forming part of Letters Patent No. 508,852, dated November 14, 1893.

Application filed May 26, 1892. Serial No. 434,416. (No model.)

To all whom it may concern:

Be it known that I, GILBERT B. SNOW, of Elgin, Kane county, Illinois, have invented a new and useful Improvement in Windmills, 5 of which the following is a specification.

The object of my invention is to make a simple, economical and efficient windmill; and the invention consists in the features and combinations hereinafter described and claimed.

10 In the accompanying drawings, Figure 1 is a broken sectional elevation of part of the upper portion of a windmill provided with my improvements; Fig. 2 a vertical sectional view on line 3 of Fig. 1; Fig. 3 a broken elevation 15 of a portion of the wind wheel showing the connection between the sails and arms; Fig. 4 an enlarged sectional elevation of one of the pivotal sections between the fan and arm portions of the wheel; Fig. 6 an elevation of 20 the tower; Fig. 8 a sectional elevation of the step or bearing for the vertical power shaft which is connected to the horizontal power shaft; Figs. 5, 7, 9 and 10 detail views of parts, Fig. 10 showing the inner portion of one of 25 the flat levers used for operating the sails or fans; and Fig. 11 a plan sectional elevation showing the position of the horizontal shaft and wind wheel with reference to the vertical shaft or pivotal point of the mill.

30 A is the tower, and *a* a metallic ring or cap at the top thereof; B the main frame having a loose bearing in the ring *a*; *b* an outwardly extending arm or part thereof, and *b'* a box or bearing therein; C a horizontal shaft, and 35 *c* a gear on the inner end thereof; D the spider; E flat levers for operating sails or fans; F a sliding head loosely mounted on the shaft C, and provided with arms *f*; G a step, base or support for the ball bearing, and *g* the cap 40 portion thereof; H mechanism for shifting the sails, and *h* a sleeve or tube connecting the upper end thereof to a rod attached to the bell crank; I a counter shaft mounted above the shaft C, having a pinion *i* on one 45 end meshing with the gear, and also a beveled gear *i'* meshing with the beveled pinion *j* and vertical power shaft J, and *i'* boxes or brackets connecting the horizontal shaft and counter shaft together; L bearing plates

50 bolted to the outer end of the arm of the windmill and supporting the fan sections through the medium of a plate, *l*, to which they are rigidly fastened, *l'*, a slot in one end of the bearing plate, and *l''* an eye bolt fitting in the arm; M the step plate, base or support 55 for the vertical shaft, *m* slots therein forming ears, and *m'* a yoke connecting the gearing of the vertical and horizontal shaft; and N braces securing the tower together, and *n* hooks or turned portions at the lower ends 60 thereof.

The mechanism for shifting the sails of the windwheel is connected at its upper end to a sleeve or tube which passes through the lower bearing of the main frame, and on the 65 upper end of this tube is attached a head from which a rod extends upwardly to a bell crank fulcrumed in the arm *b* of the frame, to one arm of which it is attached. To the other arms of the bell crank I attach bearing 70 rods or links, which connect with a sliding head. As the construction and operation of these parts will be apparent from the drawings, further description thereof is considered unnecessary.

75 In windmills as heretofore constructed, it has been found difficult to overcome the heavy side draft to which the mill is subjected by reason of the tendency of the upright shaft to twist, which causes the mill "to 80 creep" and the horizontal shaft to get out of position with reference to the course on the wind. In actual operation the torsion on the upright shaft, caused by the resistance of the machinery which it drives, gradually twists 85 the wind wheel out of line or direction of the wind, which results in partial or total loss of power. The first object of my invention is to overcome this objection, which I do by so forming the horizontal shaft and its connections that it occupies an off-center position 90 toward the side to which the mill tends "to creep."

95 In constructing my improved windmill, I connect the main horizontal and counter shafts together by boxes or brackets, so cast as to form bearings for both said shafts, and thus cause them at all times to occupy the

same relative position with reference to each other. In other words, I form in each of the boxes or brackets a bearing for the horizontal shaft which shall always occupy a certain 5 definite and fixed position with reference to the bearing for the counter shaft in the same box or bracket. In ordinary mills, I find it advisable to so place the horizontal shaft that its inner end shall be off the center about 10 three inches at one side, of the vertical shaft, which passes through the pivotal point of the mill while the outer end bearing the wind wheel is on the center—that is, in line with the direction of the wind and vertical shaft or 15 pivotal point of the mill. I do this by forming the bearings in the boxes or brackets in such way that when the horizontal and counter shafts are put in place, the former will have its outer end in line with the direction of the 20 wind and vertical shaft, and its inner end in advance of the vertical shaft in the direction toward which the mill has a tendency to creep. (See Figs. 2 and 11.) The result is that the 25 horizontal shaft being thus rigidly set, the mill has a constant tendency "to creep" into position, and not out of position, with reference to the course of the wind.

In windmills as heretofore constructed, it has been found difficult to make a light and 30 durable connection between the arm and wind wheel, and there has been no way of taking up the slack caused by wearing away of the bearings.

The second object of my invention is to 35 overcome this difficulty, which I do by making a bearing between the arm and fan, having some or all the following peculiarities: The bearing consists essentially of two plates formed with slots, and adapted to be secured 40 by a bolt passing through the slots, the bolt also serving to secure the plates to the arm, inserted between them, by passing through a hole therein. An eye-bolt may be inserted in the lower end of the arm, and the bolt securing 45 the parts together passed through its eye. This eye-bolt may be provided with screw threads on its lower end, or other means may be employed for producing adjustment. The fan sections are connected to the bearing 50 plates by means of a tilt bar fitting in the bearing thereof. Each end of the tilt bar is provided with a ball, and each bearing plate with a corresponding socket, so that the ends of the tilt bars rest in their bearings after the 55 manner of a ball and socket joint, thus leaving the sections free to adjust themselves to different positions as required by varying currents of wind. The socket or bearing surface itself is preferably large, to increase its 60 durability. When the bearing has become worn, the slackness or wear may be taken up by forcing or moving the bearing plates up by means of a nut on the lower end of the eye-bolt, or in any other convenient way. As 65 will be seen, this connection between the fan sections and arms is light and durable, and

provides for adjustment in such a way as to take up the wear or slack as desired.

In windmills as heretofore constructed, there has been no way of allowing the step or 70 bearing for the vertical shaft at the lower end thereof to adjust itself to different positions as required by the slackening or loosening incidental to wear.

The third object of my invention is to overcome this difficulty, which I do by providing for automatic adjustment of the vertical shaft on the step plate. As the vertical shaft wears down into the step-plate, the yoke and gearing adjust themselves to the changed position 80 resulting from wear. I provide for this adjustment by forming the step-plate with upwardly projecting ears, and placing the lower ends of the yoke between the ears. See Figs. 9 and 10. Set screws passing through the 85 ears from either side, see Fig. 10, serve to hold the yoke and gearing steady; but the set screws should not be tightened to an extent that will interfere with the automatic adjustment of the yoke and gearing as required by 90 wear. In this way, I prevent binding resulting from wear, and secure ready automatic adjustment of the parts mentioned.

It will of course be understood that I do not intend to limit myself to minor features 95 or details of construction, or to the use of all my improvements together in a single windmill. On the contrary, I intend to vary form and construction, and to omit parts or use equivalents as circumstances may suggest or 100 render expedient.

I claim—

1. In a windmill, a main horizontal shaft having its outer end secured on the center or in line with the direction of the wind and 105 vertical shaft, and its inner end in an off-center position or in advance of the vertical shaft toward the side to which the mill tends to creep, whereby the wind wheel is held in proper position with reference to the 110 wind, substantially as described.

2. In a windmill, the combination of a main horizontal shaft having its outer end secured on the center or in line with the direction of the wind and vertical shaft, and its inner 115 end in an off-center position or in advance of the vertical shaft, a counter shaft, and boxes or brackets securing the two shafts together and having a bearing therein for each, whereby the two shafts are held in fixed position with reference to each other, and the wind wheel in proper position with reference to the wind, substantially as described.

3. In a windmill, the combination of fan 125 sections each provided with a tilt bar having a ball at its respective ends, an adjustable bearing formed of slotted plates bolted to the arm, each having a socket corresponding to the balls of the tilt bar, the bearing plates being provided with an eye-bolt screw-threaded at its lower end and a nut thereon for taking up slack produced by wear,

and the tilt bar and bearing plates being secured together by the balls fitting into their respective sockets, substantially as described.

4. In a windmill, the combination of a step-plate for the vertical shaft at the lower end thereof, and a yoke connecting the gearing and vertical and horizontal shafts loosely secured to the step-plate, whereby binding is

prevented and the yoke and gearing enabled to adjust themselves to changed positions resulting from wear, substantially as described.
